UNITED STATES PATENT OFFICE.

GEORGE BADICH, OF KNOXVILLE, TENNESSEE.

NONSLIPPING SHOE TONGUE.

1.419.199.

Specification of Letters Patent. Patented June 13, 1922.

Application filed March 1, 1922. Serial No. 540,194.

To all whom it may concern:

Be it known that I, GEORGE BADICH, a citizen of Hungary, residing at Knoxville, in the county of Knox and State of Tennessee, have invented certain new and useful Improvements in Nonslipping Shoe Tongues, of which the following is a specification.

This invention relates generally to shoes, having more particular reference to a means for holding the tongue of the shoe in a central position at the front of the upper.

The invention has for a general object to provide a novel and simple means for the above purpose, and further to provide a means whereby the shoe lace is caused to hold the tongue against lateral displacement.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of a shoe having the invention applied thereto.

Fig. 2 is a detail face view of the tongue of the shoe.

Fig. 3 is a horizontal section on the line 3-3 of Fig. 2.

Fig. 4 is a face view of an attachment whereby the invention may be applied to a shoe already made or in use.

Fig. 5 is a perspective view showing another form of attachment which may be applied to a shoe already in use.

In Fig. 1 of the drawings the reference numeral 10 indicates in general the upper of an ordinary laced shoe which is split as at 11 for the insertion and removal of the foot, an ordinary crossed lacing 12 being used to draw the edges together. The tongue is shown at 13.

In shoes as ordinarily worn this tongue has a tendency to slip to one side or the other, causing the shoe to present an unsightly appearance, and also exposing the stocking to becoming wet, in rainy weather.

According to my present invention I pro-

vide an attachment whereby the lace is engaged with the tongue to prevent this displacement of the tongue. As shown in Figs. 1 to 3 a pair of longitudinal slits 15 is formed in the tongue midway between opposite sides thereof, causing the tongue to present between said slits a loop 16 through which the two reaches of the laces can be passed as shown. The tongue is here shown as having 60 stitched thereto a backing member 17, while a small pad 18 of felt or the like is inserted between the tongue and backing member behind the looped portion 16. The length of this looped portion 16 is preferably such as 65 to receive the crossed lace elements leading both upward and downward from one pair of eyes and to closely engage at its ends said lace elements at the point where they cross one another, the lace elements being passed 70 through this loop when the shoe is being laced, as will be understood. The diagonal arrangement of the lace elements acts to prevent the loop moving therewith and holds the tongue centrally positioned. 75

In the attachment shown in Fig. 4 a leather piece 20 of a corresponding shape to the top portion of the tongue is adapted to be sewn on any ordinary tongue. This leather piece is formed with a pair of slits 21 to 80 provide a loop 22, a small backing piece being sewn on behind this loop.

In Fig. 5 I have shown a different attachment in the form of a metal plate 25, which is provided with apertures 26 to receive 85 threads whereby it may be secured to any tongue. This plate has at each end a series of clips comprising a central one 27 and a pair of diagonally projecting side ones 28 under which the lace elements engage as 90 shown. This attachment may be colored in correspondence to the tongue, or it may be plated and polished to impart an ornamental appearance.

Having thus described my invention what 95 I claim as new and desire to protect by Letters Patent of the United States is as follows:

1. An attachment for shoes comprising a plate adapted to be secured to the tongue 100 thereof, said plate having clips projecting from opposite ends, said clips being adapted

to project over the face of the tongue and to receive a shoe lace between themselves and the tongue, for the purpose specified.

2. An attachment for shoes comprising a plate adapted to be secured to the tongue thereof, said plate having clips projecting from opposite ends, each end of said plate presenting a central longitudinally extend-

ing clip, and a pair of diagonal side clips said clips being adapted to project over the face of the tongue and to receive a shoe lace between themselves and the tongue, for the purpose specified. 10

In testimony whereof I have affixed my signature.

GEORGE BADICH.
